(57) **CLAIM**

The ornamental design for a double-side pocket folder, as shown and described.

DESCRIPTION

FIG. 1 is a front elevational view of a double-side pocket folder showing my new design, the rear view being a mirror image thereof;

FIG. 2 is a right side elevational view thereof, the left side view being a mirror image thereof;

FIG. 3 is a top plan view thereof;

FIG. 4 is a bottom plan view thereof;

FIG. 5 is a top, front, left side perspective view thereof;

FIG. 6 is a cross-sectional view taken along line 6—6 of FIG. 1; and

FIG. 7 is a cross-sectional view taken along line 7—7 of FIG. 1.

FIG. 8 is a front elevational view of a double-side pocket folder made of transparent material, showing my new design, the rear view being a mirror image thereof;

FIG. 9 is a right side elevational view thereof, the left side view being a mirror image thereof;

FIG. 10 is a top plan view thereof;

FIG. 11 is a bottom plan view thereof;

FIG. 12 is a top, front, left side perspective view thereof;

FIG. 13 is a cross-sectional view taken along line 13—13 of FIG. 8; and,

FIG. 14 is a cross-sectional view taken along line 14—14 of FIG. 8.
